Primary Examiner — Cary M Robinson*Assistant Examiner* — Emily Anna Saunders(74) *Attorney, Agent, or Firm* — Wissing Miller LLP(57) **CLAIM**

The ornamental design for a helical toy paddle, as shown and described.

DESCRIPTION

FIG. 1 is a perspective view of the helical toy paddle in an environment of use;

FIG. 2 is a top perspective view of the helical toy paddle showing our design;

FIG. 3 is a top view thereof;

FIG. 4 is a front view of the helical toy paddle, wherein the rear view is a mirror image thereof;

FIG. 5 is a bottom perspective view of the helical toy paddle;

FIG. 6 is a left side view thereof; and,

FIG. 7 is a right side view thereof.

The broken lines in the drawings that depict portions of the helical toy paddle form no part of the claimed design. The broken lines showing the helical toy in FIG. 1 are for the purpose of illustrating the environmental subject matter and form no part of the claimed design.
